CLAIM

The ornamental design for a connector assembly, as shown and described.

DESCRIPTION

FIG. 1 is a perspective view of the connector assembly;

FIG. 2 is a bottom perspective view thereof;

FIG. 3 is a top plan view thereof;

FIG. 4 is a bottom plan view thereof;

FIG. 5 is a right side elevational view thereof, the left side elevational view being a mirror image thereof;

FIG. 6 a front elevational view thereof; and,

FIG. 7 is a back elevational view thereof.

Where utilized, phantom lining is for illustrative purposes only and is not intended to limit or form any part of the claimed design.

1 Claim, 5 Drawing Sheets
